UNITED STATES PATENT OFFICE.

WALTER KNOWLES TROTMAN, OF HOLYOKE, MASSACHUSETTS, ASSIGNEE OF ONE-HALF TO CHARLES DRURY JACOBS, OF SOUTH ORANGE, NEW JERSEY.

APPARATUS AND PROCESS OF PRODUCING TORN-EDGE PAPER SHEETS.

Application filed April 25, 1918. Serial No. 230,659.

To all whom it may concern:

Be it known that I, WALTER KNOWLES TROTMAN, a subject of the King of Great Britain and Ireland, and a resident of Holyoke, in the State of Massachusetts, have invented certain new and useful Improvements in Apparatus and Processes of Producing Torn-Edge Paper Sheets, of which the following is a specification.

10 The invention relates to a mechanism and process for automatically producing torn edges on all four edges of the sheets, that is, on both the transversely located or disposed edges of the sheets to be formed, as well as 15 on the transversely located or disposed edges thereof, as the paper is formed in a layer or web from the pulp. In the illustrated embodiment, the invention is exemplified as applied to the manufacture of paper by 20 means of a paper forming cylinder rotating in a pulp vat; although the invention can be applied with other kinds and forms of paper making mechanism.

Further objects and advantages of the invention will be set forth in part hereinafter, and in part will be obvious herefrom, or may be learned by practice with the invention; such objects and advantages being realized and attained through the steps, means 30 and combinations pointed out in the appended claims.

The invention consists in the novel steps, processes, parts, constructions, arrangements, combinations and improvements herein shown and described.

The accompanying drawings, herein referred to and constituting a part hereof, illustrate one embodiment of the invention, and together with the description serve to 40 explain the principles thereof.

Of the drawings:—

Fig. 1 is an elevation of a paper making cylinder, with various parts broken away to illustrate other parts;

45 Fig. 2 is an end elevation and several fragmentary transverse sections transversely of Fig. 1;

Fig. 3 is a fragmentary enlargement of the gauze sheet fastening devices;

50 Fig. 4 is a side elevation of the cylinder of Fig. 1 and showing the deckle edging devices;

Fig. 5 is a diagrammatic section of the edge producing members; and

55 Fig. 6 is a diagrammatic showing of the

devices for completing the making of the paper.

As stated in the illustrated exemplification of the invention, a paper forming cylinder 1 is employed, which may be of any suitable or approved construction. As shown, the cylinder 1 comprises a plurality of circular discs 2 mounted on a shaft 3. The cylindrical frame thereof is formed over and along the discs 2, and as embodied, comprises longitudinally disposed rods 4, attached in spaced relation around the discs 2 and supported by the peripheries thereof.

About the exterior of the rods 4 are wound or disposed a wire or wires 6, arranged either circularly or spirally, the wire or wires being soldered or otherwise suitably fastened to the rods 4. Upon the cylindrical backing thus formed, in the present embodiment, is secured a wire gauze sheet 7, which forms the outer surface of the cylinder structure proper.

About the exterior of the cylindrical gauze covering 7 is detachably fastened a sheet of relatively fine gauze 8, which sheet carries the devices for producing the deckle edges. The sheet 8 is detachable from the cylinder and is interchangeable with and replaceable by other similar sheets. In the embodied form of fastening means, the sheet 8 has fixed thereto along one of its transverse or uncurved edges, a bar 10 which bar extends into a transversely disposed recess 11 located in the cylinder between successive parts or portions of the covering 7.

The bar 10 has apertures 13 formed therein, in which the fastening devices of the cylinder engage to hold the sheet 8 upon the cylinder. Said fastening devices comprise on one side of the recess 11, fixed pins 14 which engage with the holes 13 in the bar 10 which as stated is fastened to one end of the sheet 8. At the other side of the recess 11 is a movable bar 15 having thereon pins 16, which engage with the holes 13 in the similar bar 10 which is fastened to the other end of sheet 8, or to another sheet 8, in case there are several extending around the cylinder. There may be, of course, one or more sheets 8 about the cylinder.

For the purpose of moving bar 15 to and fro to effect the fastening and unfastening of the sheet 8, as embodied, the bar is mounted on a rod 17, which rod extends along the cylinder and is mounted to rock 110

in the heads or end disc 2 of the cylinder 1. For the purpose of rocking the rod 17, there is secured thereto a plate 18 having on its edge a gear sector 19, the other end of the plate 18 being yoked about the rod 17, the yoke and rod being fastened together by a pin 20.

Meshing with the gear sector 19 is a worm gear 21, which is journaled at 22 and 23 in 10 a bracket 24 fixed to one of the heads or end discs 2 of cylinder 1. On one end of the worm gear 21 is a pinion 25, which meshes with a worm gear 26, formed on a shaft or rod 27, which latter extends longitudinally of the cylinder 1 and is rotatably journaled in the end discs or heads 2 thereof. The mechanism just described may be duplicated at each end of the cylinder if desired, and a crank or wrench may be used to turn 15 rod 27.

It will be understood that the bar 10 at one end of the gauze sheet 8 is fitted over pins 14 and the sheet stretched about the surface of the cylinder. The bar 15 is then 20 placed in position in the recess 11 with the pins 16 in holes 13 in the bar 10 and the shaft 27 is turned to rock bar 15 and thus draw the sheet 8 taut about the cylinder.

The devices for producing the torn edging, 25 which devices may be conveniently called attenuators, are carried upon the surface of the gauze sheet 8 and as embodied comprises one or more wires or bars 30 attached to the surface of sheet 8 by stitching, soldering or otherwise, these wires or bars extending 30 about the cylinder, that is, longitudinally of the web of paper being formed, and projecting into the layer of pulp on the surface of the cylinder as it comes up out of the 35 pulp vat.

Other wires or bars 31 are likewise fastened to the surface of the gauze sheet 8 at 40 right angles to the wires or bars 30, that is, along the cylinder and transversely of the web of paper being formed. In practice the members 30 are higher than the members 31 to effect the longitudinal separation during the drying and shrinkage of the web or layer. Lighter wires or bars 32 45 may be arranged parallel to and between both the wires or bars 30 and 31, but as they do not project so far into the layer of pulp which is forming into paper on the cylinder, they do not effect a thinning of the pulp layer sufficiently to make a torn edge but merely serve to mark the edges 50 of smaller sheets.

The pulp thinning members 30 and 31 project into the layer of paper-forming fiber, which the cylinder has lifted upon the covering 8 from the pulp mixture, and are of a height nearly equal to the thickness 55 of the pulp layer upon the cylinder. The layer is thus very thin over the devices 30 and 31.

The layer of pulp passes from the cylinder 1 to couch rolls or drying felts 35, whereby more of the moisture is pressed out and the fibre is consolidated, in a well known manner. The web then passes on to the 70 press rolls 36, drying rolls 37 and the calenders 38 in the usual manner as diagrammatically shown in Fig. 6.

As the web of paper dries it is subject to transverse shrinkage, and by reason of the 75 thinning thereof along longitudinal lines by the members 30, the paper breaks or almost breaks along these longitudinal lines into a deckle edge. When it does not entirely separate, it may be pulled apart with but little 80 effort, thus forming a torn edge along longitudinal edges of the sheets, referred to the web of paper from which they are formed. Thus the longitudinal torn edging is by the present invention caused to take place automatically or sequentially in the manufacture 85 or making of the paper and by the contracting or drying of the layer or web of paper. The transverse torn edging is effected in the usual manner, the sheets pulling apart in the winding rolls 39. Thus by my invention there is effected automatically torn edges on all four edges of a sheet herefore possible and attainable only in the 90 expensive hand-made papers.

It will be understood that changes may be made from the details illustrated and described, within the scope of the appended claims, without departing from the principles of the invention and without sacrificing 95 its chief advantages.

I claim—

1. In a paper making cylinder, devices for producing sheets having four defined tearable edges from a pulp layer, including 105 pulp thinning members disposed around the cylinders and pulp thinning members disposed along the cylinder, the pulp thinning members about the cylinder and those along the cylinder being of different heights, 110 whereby the paper edges along the cylinder and those about the cylinder will tear automatically under different strains.

2. In a paper making cylinder, devices for producing sheets having four defined 115 tearable edges from a pulp layer, including pulp thinning members disposed around the cylinders and pulp thinning members disposed along the cylinder, the pulp thinning members along the cylinder being of less height than those disposed around the cylinder, whereby the paper edges along the cylinder and those about the cylinder will tear automatically under different strains.

3. In a paper making cylinder, devices 125 for producing torn edges on all four edges of the sheet, including a plurality of circular pulp thinning members surrounding the cylinder, but of less height than the pulp layers, a plurality of straight pulp 130

thinning members spaced apart and disposed along the cylinder and intersecting the circular pulp thinning members, said circular and straight pulp thinning members being of different heights, circular pulp thinning members surrounding the cylinder and located between said first mentioned circular pulp thinning members, and straight pulp thinning members disposed along the cylinder between said first mentioned straight pulp thinning members, said last mentioned circular and straight pulp thinning members being of different height from those first mentioned, but none of the members being of as great height as the thickness of the pulp layer, so as to form torn edges on all the edges of each sheet of the paper.

4. In a paper making cylinder, devices for producing torn edges on all four edges 20 of a sheet, including a plurality of circular pulp thinning members surrounding the cylinder, but of less height than the pulp layer, a plurality of straight pulp thinning

members spaced apart and disposed along the cylinder and intersecting the circular 25 pulp thinning members, said circular and straight pulp thinning members being of different heights, circular pulp thinning members surrounding the cylinder and located between said first mentioned circular 30 pulp thinning members, and straight pulp thinning members disposed along the cylinder between said first mentioned straight pulp thinning members, said last mentioned circular and straight pulp thinning members 35 being of less height than either the circular or straight pulp thinning members first mentioned.

In testimony whereof, I have signed my name to this specification, in the presence of 40 two subscribing witnesses.

WALTER KNOWLES TROTMAN.

Witnesses:

SELM NEWELL,
F. HENRY SAVAGE.
